William C. Wren.

UNITED STATES PATENT OFFICE.

WILLIAM C. WREN, OF BROOKLYN, NEW YORK.

IMPROVEMENT IN METALLURGIC GAS-FURNACES.

Specification forming part of Letters Patent No. 140,606, dated July 8, 1873; application filed April 19, 1873.

To all whom it may concern:

Be it known that I, WILLIAM C. WREN, of the city of Brooklyn, county of Kings, State of New York, have invented a new and Improved Method of Heating Smelting-Furnaces by the use of Gas; and I do hereby declare that the following is a full and exact description thereof, reference being had to the accompanying drawings and the letters of reference marked thereon.

My invention relates to the method and manner of heating smelting or other furnaces that require a high degree of heat by gas and air from a forced blast. The second part relates to the method of distributing the gas and air over large surfaces in large furnaces.

Figure 1 is a sectional view of a furnace with my attachment in place. Fig. 2 is a sectional view of the compound blast and gas pipe.

A is the gas-pipe, with the inlet at D. B is the blast-pipe, introduced through the bottom of, and into the gas-pipe A, and carried into the pipe A, so that the outlet end of the pipe B is four or four and a half inches short of the outlet end of the pipe A.

Having the compound air and gas pipes made in the manner described, or several of them, if the furnace to be heated requires them, I fill the space with brick, usually occupied by the coal, up to within six or eight inches of the arch of the furnace, if possible; and introduce the pipes through the bottom in the manner shown, Fig. 1. I prefer to bring

the pipes from the bottom, so that the flame can play against the arch, if possible. The compound pipes can enter from the sides, or end, according to circumstances. I connect the blast to the pipe B in such a manner that the wind will come from the fan, or other kind of power blast, in as direct a line as possible, with the inside wind-pipe B not as long as the outside pipe A, by four inches and a half. I find, having the wind-pipe B inside the gas-pipe, and the distance named shorter than the gas-pipe, to be the best, and also with a cock on the gas-pipe D, marked E, and a cock on the wind-pipe B, marked F, to regulate the flow of both gas and wind in the right proportions. If one compound pipe is not enough for the width of the furnace, add as many more compound pipes as may be necessary, each one the counterpart of the other.

What I claim as my invention is—

1. The compound air and gas pipe herein described, made by arranging the air-blast pipe inside the gas-pipe, substantially as specified.

2. The arrangement of the air blast and gas pipes, the former within and shorter than the latter, and provided with suitable regulating valves or cocks, as set forth.

WILLIAM C. WREN.
